ABSTRACT OF THE DISCLOSURE

Detergent active materials which are effective in the absence of phosphate builders comprise sulfur-linked linear alkyl vicinal disulfates of the formula:

in which Y is

R and R₁ are hydrogen or alkyl radicals having a total of from 9 to 23 carbon atoms, and X is hydrogen or a water-soluble salt-forming cation.

BACKGROUND OF THE INVENTION

This invention is concerned with sulfur-linked linear alkyl vicinal disulfates which are effective as heavy duty detergent active material.

Increased concern over water pollution has produced significant changes in household detergents. Initially, major emphasis has been placed on producing biodegradable surface-active components for detergents. The shift to linear surface-active materials, including linear alkylbenzene sulfonate (LAS) and alpha-olefin sulfonates, etc., has reduced pollution attributed to nonbiodegradability.

However, the above-mentioned surface-active materials are inadequate in terms of soil removal in the absence of phosphate builders. Increasing evidence appears to indicate that phosphates contribute to the growth of algae in the nation's streams and lakes. This algae growth poses a serious pollution threat to the maintenance of clear, good domestic water supplies.

Consequently, there has developed a need for detergent active materials which will function successfully in the absence of phosphate builders. Recently, certain non-phosphate building materials have been proposed as replacements for the phosphates. Thus, materials such as the polysodium salts of nitrilotriacetic acid, ethylene diamine tetraacetic acid, copolymers of ethylene and maleic acid, and similar polycarboxylic materials have been proposed as builders. These materials, however, when employed with conventional detergent actives such as LAS, have, for one reason or another, not proved to be quite as effective as phosphates in detergent formulations. For example, some of the materials have proven to be insufficiently biodegradable to meet present and anticipated requirements.

It is therefore desirable to provide compounds which are effective as detergent active materials in the absence of phosphate builders and are also sufficiently biodegradable that their use results in contributing neither foam producers nor phosphates to the water supply.

SUMMARY OF THE INVENTION

Effective heavy duty detergent compositions which may

2

be formulated without the necessity of phosphate builders are provided. These formulations employ as detergent active materials sulfur-linked linear alkyl vicinal disulfates of the formula:

in which Y is

15 R and R₁ are hydrogen or alkyl radicals having a total of from 9 to 23 carbon atoms, and X is hydrogen or a water-soluble salt-forming cation. In a preferred form Y is

20 and X is an alkali metal cation. It is also preferred that the sum of the carbon atoms in R and R₁ be in the range of 13 to 19 carbon atoms.

25 The compounds of this invention do not require the presence of a phosphate builder to achieve good detergency. They achieve excellent detergency with such materials as the sodium salts of nitrilotriacetic acid and polycarboxylates such as ethylene-maleic anhydride copolymer. The materials, however, may be employed in the absence of any builder.

DESCRIPTION OF PREFERRED EMBODIMENTS

30 The salt-forming cation X may be any of numerous materials such as alkali metal, alkaline earth metal, ammonium, or various organic cations. Examples of suitable organic cations include amino materials such as those of the following structure:

35 The alkali metal cations are preferred, and sodium ions are particularly preferred.

40 The alkyl groups represented by R and R₁ are, as previously noted, linear, although the presence of a random methyl radical upon the linear chain, for example, may not adversely affect the performance of the compound. Alkyl radicals representative of R and R₁ include hexadecyl, heptadecyl, octadecyl, nonadecyl, eicosyl, heneicosyl, and docosyl. Heptadecyl, octadecyl, nonadecyl, eicosyl, and heneicosyl groups are preferred. In a preferred form the materials are formed by the reaction of thioglycerol with an alpha olefin and thus one or the other of R and R₁ will be hydrogen.

45 55 The detergent active compounds of this invention are preferably prepared by reacting a linear monoolefin, preferably an alpha olefin, with thioglycerol giving a compound having two vicinal hydroxy groups. The hydroxy groups are then sulfated by conventional techniques giving a compound containing two sulfate groups and a sulfide linkage in the backbone. This compound, while being an adequate detergent, is sensitive to bleaching and in the preferred embodiment the sulfide prior to sulfation is oxidized to a sulfoxide or a sulfone or a mixture thereof.

60 65 The products then obtained by sulfation are excellent detergents and are bleach stable.

70 The reaction of the olefin and the thioglycerol is accomplished by simply heating the materials together followed by recrystallization from conventional solvents such as ethanol or benzene. The sulfation of the dioxy compound is effected by conventional sulfation techniques employing sulfur trioxide, chlorosulfonic acid, oleum,

sulfuric acid, etc., in a ratio of at least 2 mols of sulfating agent per mol of diol. Ratios of from 2 to 10 are preferred. When it is desired to oxidize the sulfide group prior to sulfation, this is accomplished again by conventional techniques employing as oxidizing agents hydrogen peroxide, metal hypohalites, etc.

The following examples illustrate the preparation of the compounds of this invention.

EXAMPLE 1

Addition of thioglycerol to 1-hexadecene

A 500 ml. flask was charged with 112 g. (0.5 mol) of 1-hexadecene, 71.5 g. (0.6 mol) of thioglycerol, and 100 ml. of ethanol. The mixture was placed upon a hot plate and heated overnight at 50-70° C. The mixture, originally in two layers, had become homogenous. It was allowed to cool to room temperature and then further cooled with ice. The solid product in the flask was removed by filtration and recrystallized from ethanol. The product was dried in a 50° C. oven overnight and gave a yield of 126 g. of a white solid which melted at 71-72° C. and by IR analysis showed two types of —OH absorption and no remaining olefin bonds.

EXAMPLE 2

Addition of thioglycerol to 1-eicosene

The procedure of Example 1 was followed employing 140 g. (0.5 mol) of 1-eicosene instead of hexadecene. After recrystallization from ethanol there was obtained 166.6 g. (85.9% yield) of a white solid which showed by IR analysis two types of —OH absorption and the presence of a small amount of alpha olefin. The product was recrystallized from benzene to give a white solid, melting point 82-83.5° C., an IR analysis of which showed no remaining olefin bonds.

EXAMPLE 3

Addition of thioglycerol to 1-docosene

The procedure of Example 1 was followed employing 154 g. (0.5 mol) of 1-docosene. The product recrystallized from benzene was 183 g. (88% yield) of a white solid having a melting point of 87-88° C.

EXAMPLE 4

Oxidation of eicosene-thioglycerol adduct

15.1 g. (0.039 mol) of the product of Example 2 and 60 ml. of glacial acetic acid were placed in a 125 ml. flask equipped with a magnetic stirrer. A thermometer was inserted and 10.5 ml. (0.084 mol) of 30.6% H₂O₂ was added slowly and with stirring. The maximum temperature reached without the application of external heat was 50° C. The temperature was raised to 80° C. and maintained for 1½ hours. The mixture was cooled in ice and the product collected by suction. The white solid thus obtained was recrystallized from benzene to give 14.7 g. (90.0% yield) of product as white needles, melting point 112-113° C., whose IR spectra showed a strong band at 1120 cm.⁻¹ (—SO₂) and nothing at about 1000 cm.⁻¹ (—SO—).

EXAMPLE 5

Sulfation of oxidized hexadecene-thioglycerol adduct with SO₃

276 mg. (0.6 mmol) of a sulfone-containing material prepared according to the procedure of Example 4 from the product of Example 1 was placed in a 100 ml. stoppered graduated cylinder containing 10 ml. of CCl₄ and a magnetic stirring bar. The mass was heated to dissolve, then stirred and placed in an ice bath. The precipitate was uniformly fine. After flushing with N₂, 0.1 ml. of SO₃ was added dropwise to the cold suspension. The mixture turned yellow and dissolved. The cylinder was removed from the ice and an additional 0.1 ml. of SO₃ 75

was added dropwise. The color darkened. A 1 ml. sample was titrated with Hyamine showing the presence of 1.9 sulfate groups per molecule. The CCl₄ was removed from the remainder of the solution, water was carefully added, and the whole was neutralized to a pH of 10 (pH meter) with NaOH solution.

EXAMPLE 6

Sulfation of sulfoxide-containing-octadecene thioglycerol adduct

0.5 g. of an adduct of 1-octadecene with thioglycerol prepared according to the procedure of Example 1 and oxidized to contain one sulfoxide group per molecule was placed in a 250 ml. beaker and dissolved in 40 ml. of dry methylene chloride. After cooling the mixture to 10° C., 1.0 ml. of chlorosulfonic acid was slowly added by submerging the tip of an eyerodder containing the acid below the surface of the well agitated solution. The resulting solution was allowed to stand at ambient conditions for five minutes. The pH was adjusted to 8-9 with dilute sodium hydroxide. The solvent was removed by gentle warming and the residue diluted to 10 ml.

EXAMPLE 7

Sulfation of eicosene-thioglycerol adduct with chlorosulfonic acid

A 125 ml. Erlenmeyer flask was charged with 0.5 g. (1.29 mmoles) of the product of Example 2 and 40 ml. of dry diethyl ether. After cooling the mixture to 10° C., 1.0 ml. of chlorosulfonic acid was slowly added by submerging the tip of an eyerodder containing the acid below the surface of the well agitated ether solution. The resulting solution was allowed to stand at ambient conditions for five minutes. The pH was adjusted to 8-9 with dilute sodium hydroxide. The solvent was removed by gentle warming and the residue diluted to 100 ml.

Detergency of the compounds of the present invention is measured by their ability to remove natural sebum soil from cotton cloth. By this method, small swatches of cloth, soiled by rubbing over face and neck, are washed with test solutions of detergents in a miniature laboratory washer. The quantity of soil removed by this washing procedure is determined by measuring the reflectances of the new cloth, the soiled cloth, and the washed cloth, the results being expressed as percent soil removal. Because of variations in degree and type of soiling, in water and in cloth, and other unknown variables, the absolute value of percent soil removal is not an accurate measure of detergent effectiveness and cannot be used to compare various detergents. Therefore, the art has developed the method of using relative detergency ratings for comparing detergent effectiveness.

The relative detergency value is obtained by comparing 55 and correlating the reflectance value results from the test solution with the results from two defined standard solutions.

The two standard solutions are selected to represent a 60 detergent formulation exhibiting relatively high detergents characteristics and a formulation exhibiting relatively low detergents characteristics.

By testing experimental solutions against the two standardized solutions, using different portions of the same soiled cloth, the results can be accurately correlated. The two standard solutions were prepared for the following detergent formulations:

Formulation for the low detergents standard (Control A)

Ingredient:	Weight percent
Alkylbenzene sulfonate	35
Sodium tripolyphosphate	40
Water	8.5
Sodium sulfate	8
Sodium silicate	7
Carboxymethylcellulose	0.8

Formulation for the high detergents standard (Control B)

Ingredient:

	Weight percent
Linear alkylbenzene sulfonate (LAS)	7.5
Tallow alcohol sulfate	10
Sodium tripolyphosphate	47.5
Water	10
Sodium sulfate	13
Sodium silicate	5
Carboxymethylcellulose	1

The standard exhibiting high-detergent characteristics was prepared by dissolving a relatively large amount of the above formulation (Control B) (2.0 g.) in 1 liter of 300 p.p.m. hard water (calculated as $\frac{2}{3}$ calcium carbonate and $\frac{1}{3}$ magnesium carbonate). The low detergents standard contained a relative low concentration of the formula (Control A) (1.0 g.) dissolved in 1 liter of 300 p.p.m. water (same basis).

The miniature laboratory washer used was so constructed that the two standard formulations and two test formulations could be used to wash different parts of the same swatch. This arrangement ensured that all four formulations were working on identical soil (natural facial soil). Relative detergency (RD) values were calculated from soil removals (SR), according to the equation:

$$RD = 2 + 4 \frac{\text{Percent SR}_{\text{Test}} - \text{Percent SR}_{\text{Control A}}}{\text{Percent SR}_{\text{Control B}} - \text{Percent SR}_{\text{Control A}}}$$

The following table presents the detergency data on a group of representative compounds of this invention. For comparison, the detergency is given for a linear alkylbenzene sulfonate (LAS) (having from 11 to 14 carbon atom straight chain alkyl groups) both with and without a phosphate builder.

Each formulation tested comprised 25 weight percent of the test material along with 1% carboxymethylcellulose, 7% sodium silicate, 8% water, and 59% sodium sulfate. In addition, formulations were tested containing 15% of the active material and 20% of NTA.

lated with additional compatible ingredients being optionally incorporated to enhance the detergent properties. Such materials may include but are not limited to anticorrosion, antiredeposition, bleaching and sequestering agents, and certain organic and inorganic alkali metal and alkaline earth metal salts such as in organic sulfates, carbonates, or borates. Also nonphosphate builders may be included in the composition. Examples of these builders are the sodium salts of nitrilotriacetic acid, ethylene diamine tetraacetic acid, and ethylene maleic acid copolymers, etc. Also small quantities of phosphate builders may be included although, of course, they are not necessary for effective detergency.

While the character of this invention has been described in detail with numerous examples, this has been done by way of illustration only and without limitation of the invention. It will be apparent to those skilled in the art that modifications and variations of the illustrative examples may be made in the practice of the invention within the scope of the following claims.

I claim:

1. A compound of the formula:

in which Y is

25 R and R_1 are hydrogen or alkyl radicals having a total of from 9 to 23 carbon atoms, and X is hydrogen or a member of the group consisting of alkali metal, alkaline earth metal, ammonium, $\text{NH}_2^+(\text{CH}_2\text{CH}_2\text{OH})_2$, and $\text{NH}^+(\text{CH}_2\text{CH}_2\text{OH})_3$ cations.

RELATIVE DETERGENCY OF ALKYL VICINAL DISULFATES

Test materials	Compound tested	Conc.	NTA conc.	Carbon atoms in R and R_1	Relative detergency ratings in 50 p.p.m. H_2O			
					Sulfoxides		Sulfones	
					0.1% conc.	0.2% conc.	0.1% conc.	0.2% conc.
Alkyl vicinal disulfate	Alkyl vicinal disulfate	25	0	15	4.0	4.6	4.9	5.4
Do	Do	25	0	17	3.8	4.5	4.2	5.4
Do	Do	25	0	19	2.2	3.3	5.6	6.5
Do	Do	15	20	15	4.7	5.8	5.9	6.4
Do	Do	15	20	17	5.0	6.1	4.9	6.4
Do	Do	15	20	19	4.4	5.6		

The relative detergency rating for linear alkylbenzene sulfonate (LAS) (25%) was 2.9 at 0.1% and 3.9 at 0.2% concentration (50 p.p.m. water hardness). The rating for an LAS (20%)/sodium tripolyphosphate (40%) conventional built detergent was 5.8 at 0.1% and 6.1 at 0.2% concentration (50 p.p.m. water hardness). These materials were tested in formulations containing 7% sodium silicate, 1% carboxymethylcellulose, 8% water, the indicated amounts of LAS and phosphate, and sufficient sodium sulfate to give 100%.

The sulfur-linked linear alkyl vicinal disulfates may be employed in combination with other detergent active materials. They are particularly effective with other di-anionic materials, examples of which include linear alkyl and alkenyl disulfates and disulfonates. A particularly useful class of materials for use in detergent active combinations is that of linear 2-alkenyl or linear 2-alkyl 1,4-butane diol disulfates in which the alkenyl or alkyl groups contain from 15 to 20 carbon atoms.

In employing the detergent active materials of this invention in detergent compositions, they may be formu-

55 2. A compound according to claim 1 in which Y is

60 3. A compound according to claim 1 in which X is alkali metal.

4. A compound according to claim 3 in which X is Na.
